[57] CLAIM

The ornamental design of a foot operated control unit, substantially as shown.

DESCRIPTION

FIG. 1 is a side view of a foot operated control unit showing my new design;

FIG. 2 is a top view thereof;

FIG. 3 is a side view of the side opposite to that shown in FIG. 1;

FIG. 4 is a bottom view thereof; and

FIGS. 5 and 6 are, respectively, front and rear elevational views thereof.
